(57) **CLAIM**

The ornamental design for cleaning implement, as shown and described.

DESCRIPTION

FIG. 1 is a perspective view of a “cleaning implement” incorporating the design of my invention

FIG. 2 is a front view thereof;

FIG. 3 is a side view thereof;

FIG. 4 is an opposite side view thereof;

FIG. 5 is a rear side view thereof;

FIG. 6 is a top view thereof; and,

FIG. 7 is a bottom view thereof.

The elements shown in broken lines illustrate environmental material and form no part of the design
